UNITED STATES PATENT OFFICE

THOMAS LA MAIDA, OF CLEVELAND, OHIO

BATHING SUIT

Original application filed October 31, 1932, Serial No. 640,522. Divided and this application filed January 16, 1933. Serial No. 651,941.

This invention relates to bathing suits, and more particularly to bathing suits of one-garment type; and it is among the objects of the invention to provide a construction which is light and comfortable while providing full coverage, and which makes important savings and advantages in manufacturing. Other objects and advantages will appear as the description proceeds.

To the accomplishment of the foregoing and related ends, the invention, then, comprises the features hereinafter fully described, and particularly pointed out in the claims, the following description and the annexed drawing setting forth in detail certain illustrative embodiments of the invention, these being indicative however, of but a few of the various ways in which the principle of the invention may be employed.

In said annexed drawing:—

Fig. 1 is a front elevational view of an embodiment of the invention; Figs. 2 and 3 are elevational views of blanks employed in assembly indicated in Figs. 5 and 6, respectively; Fig. 4 is a perspective view of the blank of Fig. 3 in a further stage of assembly; Fig. 5 is a perspective view, parts being broken away, showing another stage of assembly; and Fig. 6 is a like view of a modification.

In its general appearance, a bathing suit in accordance with the present invention has the aspects of a garment extending from the shoulders down over the thighs in continuous shirt-like or blouse-like form, extending below the bifurcation of the body, and providing concealed trunks or rather trunk-like extremities. A shoulder-thigh or shirt-like garment foundation is first prepared, and this may be made up of any usual or preferred fabric, woven or knitted, more usually knitted, and seamed as most convenient, the whole providing shoulder pieces 2 and body portion proper 3.

As shown in Fig. 2, a convenient shaping of the blanks to enter into the garment may involve a blank A of general form to provide the shoulder pieces s, and lower wing-portions w, w. The coacting blank K is also provided, such that the edge portion a—b

may be seamed to the corresponding edge portion c—d of the blank K, the edge portion e—f seamed to the edge portion d—g. The edge portion e—h is seamed to the edge portion b—i, and the edge portion h—j is seamed to the edge k—l, and the edge i—m to the edge l—n. This forms a garment having shoulder straps above and trunk portions below, the seam lines being shown in detail in Fig. 5. By also assembling a front and back cover segment M, a garment as illustrated complete in Fig. 1 results, in which the trunk portions are formed of coacting blanks, in which blank-edges directed rearwardly and blank-edges directed forwardly are joined together at a point between the legs to form downwardly-extending seams medially for each leg in the inter-leg trunk walls and concealed within a shirt-like or blouse-like exterior appearance.

In a slightly different procedure, a shirt-like foundation garment may be made up, and within the lower portion of such foundation garment I then apply, securing by sewing or other desired means, inserts F and R (Fig. 6) at the front and rear. As shown in Fig. 3, such inserts may be formed from a blank B which has a continuous lower edge 4, and a notch n in its upper edge. This blank is fastened together along its edges 5, 6, thus forming the seam 56 in Fig. 4, and it is also cut along the dotted line 7 (Fig. 3) to provide the free edges 8, 9, Fig. 4. The further steps of assembly involve the seaming together of the corresponding edges 8, 56, and the corresponding edges 9, respectively, of the front and rear blank portions, also the securing of the outer edges 10, 11, to the corresponding wall of the shirt-like foundation. The final seams 88, 99, 10', 11', 10'', 11'', assemble the form of the garment. In the forms shown in Fig. 4 and Fig. 6, the insert front and rear blanks F, R, are seamed directly to the front and rear walls respectively of the shirt-like foundation garment, and these seams extend downwardly to present a convex edge, which terminates at a point on the lower edge of the skirt which is well forward of the leg of the wearer. It may be said that the two points of termina-

nation lie along a line which is substantially tangent to both legs of the wearer, thus presenting a smooth front surface uniformly tensioned over the body of the wearer. The 5 inserts being invisible externally, have their coacting rearwardly-directed edges and forwardly directed edges joined together at a point between the legs to form downwardly-extending seams medially for each leg, completing inter-leg portions or close-fitting trunks with the coacting outside shirt-like wall, the complete garment being shown also in Fig. 1. The garment is particularly accurately held down in place when worn, by 10 the crotch-engaging saddle insert which is fastener to the front and rear walls of the shirt-like garment, and which constitutes the inner arcs of the leg-like portions whose outer arcs are the lateral walls of the garment. 15 20 In the final assembly of the pieces the respective shapes involved make possible an easy positioning for machine-seeming operation. The entire garment presents the appearance of a construction wholly unitary 25 in character, although attained very advantageously by reason of its elements of assembly.

It is thus seen that the invention provides 30 a garment of comfortable and advantageous form, aesthetic in appearance, and highly advantageous in manufacture, permitting considerable speed in operation and without undue requirement of skill, and finally very important savings in the material are possible 35 by reason of the forms of elements involved.

This application is a division of my application Serial No. 640,522, filed October 31st, 1932.

Other modes of applying the principle of 40 the invention may be employed, change being made as regards the details described, pro-

vided the features stated in any of the following claims, or the equivalent of such, be employed.

I therefore particularly point out and distinctly claim as my invention:—

1. A knitted bathing suit having a closed form-fitting crotch insert comprising a saddle having an upwardly facing concave edge extending from the front to the rear of said suit, and outwardly facing convex edges, said convex edges being seamed to said suit to form curved seam lines across the bias of the knitted goods, said seam lines flaring downwardly and outwardly and terminating at a point along a line substantially tangent to both legs of the wearer, and said saddle having downwardly extending medial seams in the inner leg walls for reinforcing the same against rolling up.

2. A bathing suit, embodying a shirt like garment, and means for holding the lower portion thereof down, said means comprising a closed form fitting crotch engaging insert saddle joined to the front and rear walls of the garment and completing the inner arcs of leg-fitting portions whose outer arcs are formed by the lateral walls of the aforesaid shoulder thigh garment, said saddle being seamed to said front and rear walls along downwardly facing convex edges, and the uppermost portion of said saddle extending from the front to the rear of said garment in a line of concave curvature, the seams between said saddle and walls flaring downwardly and outwardly and terminating at a point along a line substantially tangent to both legs of the wearer, said shirt like garment extending across the front and rear of said saddle to conceal the same.
